[57] CLAIM

The ornamental design for a controller box for electric
model cars, as shown and described.

DESCRIPTION

FIG. 1 is a front elevational view of a controller box for
electric model cars showing my new design;
FIG. 2 is a rear elevational view thereof;
FIG. 3 is a top plan view thereof;
FIG. 4 is a bottom plan view thereof;
FIG. 5 is a side view thereof;
FIG. 6 is another side view thereof;
FIG. 7 is a sectional view taken along the line I—I of
FIG. 1, with the inner construction omitted;
FIG. 8 is a sectional view taken along the line II—II of
FIG. 1, with the inner construction omitted; and
FIG. 9 is a sectional view taken along the line III—III
of FIG. 1, with the inner construction omitted.
